UNITED STATES PATENT OFFICE.

JACOB RODERBURG, OF AACHEN, GERMANY, ASSIGNOR TO AACHENER MASCHINEN-
BAU-GESELLSCHAFT M. B. H., OF AACHEN, GERMANY.

BLANK-FEEDING DEVICE FOR WIREWORKING MACHINES.

Application filed March 13, 1925, Serial No. 15,375, and in Germany March 21, 1924.

This invention relates to blank feeding devices for wire working machines of the kind including one or more rotating feed screws, and it has for its object to provide a device 5 of this kind in which the feed screws have a plurality of threads on the station where the blanks fed by them are operated upon, these threads being connected with each other by a recess which extends transversely 10 to the axis of the screw and within which the blanks are held against movement with relation to the operating tools during a partial revolution of the screws.

The present feeding mechanism is of a simple construction and is of such a nature that only the blanks which have reached the working station are brought to a standstill with respect to the tools, while all other blanks of the row of blanks fed by the 20 screws continue their forward movement.

The invention will now be described with reference to the accompanying drawing in which:

The figure is a plan view of the feeding 25 device.

The device includes two parallelly arranged feed screws *a* and *b* of the same construction. These screws are rotated with the same angular speed and in the same sense in such a direction, as indicated by arrows on the drawing, that the wire blanks *d* placed on them are moved from the left to the right. A bar *c* serves to guide the blanks *d* which bear by one end against that bar. The portion *e* of the screws lying near the station where the blanks are operated upon, is double threaded while the other portions of the screws are single threaded. The bottoms of the two threads of each screw are in communication with each other by a recess *f* extending transversely to the axis of the screw. As soon as a blank coming from the left has entered the recess *f* it remains at a standstill therein during a partial revolution of the screws. During this time the blank is worked upon by the tools. According to the embodiment shown in the figure, the blanks *d*¹, *d*², *d*³, *d*⁴ moving towards the working station and the blanks having already undergone its operation are conveyed from the left to the right, while the blank *d*⁵ under operation is at a standstill. The device described is more particularly designed for use in connection with ma-

chines for treating needles, spokes of bicycles and similar wire-shaped blanks.

The screw is provided with two threads *x* and *y* which are in communication with each other through the recess *f*. The thread *x* extends by its last helical turn *x*⁰ beyond the recess *f* and it may even be extended up to the other end of the screw. The other thread *y* is similarly arranged, its first turn *y*⁰ beginning not at the recess *f* but at a certain distance ahead of the recess *f*. It would of course be sufficient to have the two threads extend only up to the recess *f*. The blanks are held in the positions indicated by using two parallel feed screws of the same kind. As the blanks *d* extend in the same direction as the recess *f*, the blanks conveyed by the thread *x* towards the recess *f* will not pass across the recess into the turn *x*⁰ but they will enter the recess *f* and move from the same directly into the thread *y*. On the portion *e* of the screws those turns of the threads *x* and *y* which exert a feeding action on the blanks are marked by arrows. The thread turns *x*⁰ and *y*⁰ do not take part in the feeding operation. As will be seen in the drawing, the distance by which a blank *d* is moved on between the positions *d*¹—*d*⁴ at every revolution of the screw, corresponds to a thread pitch. But between the positions *d*⁴—*d*⁵ the distance by which the blank is fed on during one revolution of the screw corresponds to only half a thread pitch, because in passing through the recess *f* the blank remains at rest for the time which the screw takes for executing half a revolution. This means that, in the embodiment illustrated, the threads *x* and *y* are staggered with relation to each other by 180 degrees.

It would not in any way influence the operation of the device if the feed screws were multiple threaded throughout and if one or certain of the threads were utilized for the feeding operation. There may also be arranged along the feed screws a plurality of working stations. At the working stations the threads may be recessed so that during the working the blank remains at rest for any desired part of a revolution of the feed screws.

The tools and any other parts of the machine are not shown and described because they do not form any part of this invention

and may be of any well-known kind and construction.

Having thus described my invention, what I claim as new and desire to secure by Letters Patent, is:

A blank feeding mechanism for wire working machines, including at least one rotating feed screw, this feed screw having several threads and a recess extending trans-

versely to the screw axis and connecting the several threads with each other, the said recess being adapted to temporarily receive the blanks fed by the screw and hold them against further movement for a time corresponding to a partial revolution of the screw.

In testimony whereof I have signed my name to this specification.

JACOB RODERBURG.
